RELEASABLE FASTENER FOR ATTACHING
CHAIRS TO FLOORS

Louis S. Zakariassen, Excelsior, Minn.

Application September 24, 1948, Serial No. 51,036

1 Claim. (Cl. 45—137)

1

This invention relates to releasable fasteners for attaching upstanding members to a base and particularly to an easily releasable fastener for securely attaching air craft seats to the floor of the plane.

In order to clean and properly maintain commercial passenger carrying air craft, it is necessary to remove all the seats in the passenger compartment. Of necessity the seats have in the past been securely bolted to the cabin floor, and it is a slow and difficult operation to remove them.

It is an object of my invention to provide a novel and greatly improved easily releasable fastener for securely attaching upstanding members to a base as in attaching air craft passenger seats to the plane floor.

It is another object to provide a fastener for positively locking chairs and seats to the floor and adapted to be easily released by a specially designed spreader tool.

It is a further object to provide a fastener capable of extremely strong and durable yet relatively light weight construction and adapted to securely attach chairs and seats to the floor and having substantially the entire mechanism concealed within the respective chair legs.

These and other objects and advantages of my invention will more fully appear from the following description made in connection with the accompanying drawings wherein like reference characters refer to similar parts throughout the several views and in which:

Fig. 1 is a horizontal sectional view taken substantially along the line 1—1 of Fig. 3 and showing a spreader tool in operative position.

Fig. 2 is a perspective view showing my improved locking device as mounted on a chair leg; and

Fig. 3 is a vertical sectional view taken substantially along the line 3—3 of Fig. 1 and showing the jaw members and retraction springs in closed locking position by full lines and in open expanded position by dotted lines.

As shown in the accompanying drawings, I provide an upstanding stud 5 permanently fixed to the floor 6 as by being bolted thereto by a nut 7. This stud 5 has a transverse horizontally disposed groove 8 formed in the periphery thereof, and said groove 8 is spaced slightly below the top extremity of the stud 5.

The lower portion of a chair leg 9 is shown in the drawings and has a central substantially cylindrical stud receiving recess 10 extending upwardly from the bottom thereof. The chair leg 9 has a pair of horizontally opposed slots formed

2

in the lower portion thereof, and these slots communicate with intermediate portions of recess 10 and extend therefrom respectively outwardly to the outside of leg 9. A pair of horizontally opposed clamping jaws 11 are respectively slidably mounted in said horizontal slots and have a pair of opposed stud gripping concave recesses 12 formed at the inner ends thereof. These recesses 12 are adapted to be received in the groove 8 of stud 5 to securely lock the chair leg 9 thereto. The outer portions of jaws 11 are diminished to respectively form gripping elements 13 at the outer extremities thereof and abutment shoulders 14 respectively adjacent the side walls of leg 9.

A pair of leaf retraction springs 15 are securely attached to the respective side walls of the leg 9 as by the attachment screws 16 and extend downwardly therefrom to overlie abutment shoulders 14. A pair of slots 17 are formed in the lower portion of said springs 15 and permit the diminished gripping elements 13 to extend therethrough. The lower free ends of said springs 15 thereby resiliently abut the respective shoulders 14 to normally hold said jaws 11 in closed or locked position. Each of the gripping elements 13 has a vertically disposed aperture 18 formed therethrough to permit a releasing tool such as the one shown in Fig. 1 to be inserted therein thereby tightly gripping elements 13 to permit expansion thereof against the force of springs 15. The tool shown in Fig. 1 will hereinafter be referred to by the numeral 19.

The operation of this fastener is obvious from the drawings and the foregoing description. The chair leg 9 is initially placed over the stud 5 which is received in the recess 10 and the jaw members 11 thereafter expanded into open position by the use of spreader tool 19 to permit the chair leg to be lowered into engagement with the floor and thereby align groove 8 of the stud 5 with the opposed jaw members 11, and thereafter the jaw members 11 are merely released and the springs 15 resiliently close the same into locking position within groove 8 to securely attach said leg 9 to the floor 6. The construction of this fastener can be made extremely durable and strong and yet much lighter in weight than the conventional cumbersome plate and bolt construction now in use.

An important feature of my improved fastener is the fact that substantially the entire mechanism thereof, when in locked position, is concealed within the chair leg. The resilient leaf springs normally lie flush against the sides of the

chair leg, and the only outstanding projections are the small smoothly rounded gripping elements 13 which extend a slight distance outwardly beyond the springs 15 to permit the spreader tool 19 to be engaged in apertures 18. It is necessary to use a spreader tool 19 because the strength of the springs 15 must be sufficient to positively lock the jaws 11 together and prevent any possibility of any inadvertent releasing thereof.

It will be seen that I have provided a highly efficient easily releasable fastener adapted to positively attach the legs of a chair to the floor of an airplane or the like to facilitate cleaning and maintaining of the airplane.

It will, of course, be understood that various changes may be made in the form, details, arrangement and proportions of the parts without departing from the scope of my invention.

What I claim is:

A releasable fastener for securely attaching each leg of a chair to the floor, each of said chair legs having a central recess formed at the bottom extremity thereof, each of said fasteners comprising an upstanding anchor stud adapted to be fixed to the floor and extend upwardly into said recess to permit the bottom of said chair leg to rest upon said floor and be supported thereby, the upper portion of said stud having a peripheral groove

formed therein in slightly spaced relation below the top thereof, a pair of horizontally opposed jaw members mounted for horizontal shifting movement in said chair leg and having opposed stud engaging recesses formed at the inner extremities thereof and normally extending into the recess of said chair leg, a pair of external leaf spring elements each having one end respectively connected to the outside of said chair leg and the other end respectively engaging said jaw members to resiliently urge the same into closed normal position and means permitting said jaw members to be externally gripped by a suitable lever operated spreader tool to permit said jaws to be released from said stud and said chair leg released from said floor.

LOUIS S. ZAKARIASEN.
